CONVERSION ARRANGEMENT FOR
SUCTION CLEANERSWilliam H. Kitto, Evanston, Ill., assignor to The
Hoover Company, North Canton, Ohio, a cor-
poration of Ohio

Application March 22, 1950, Serial No. 151,126

12 Claims. (Cl. 15—333)

1

This invention relates to suction cleaners and more particularly to an arrangement for converting a suction cleaner from on-the-floor cleaning to off-the-floor cleaning.

An object of the present invention is the provision of a converter receiving tube which is movable relative to the body of the cleaner to perform a function useful in converting the cleaner to off-the-floor cleaning in which the tube is normally locked against movement and is released for movement to operative position by the insertion of the converter tool into the converter opening.

Another object is the provision of a converter tube movable between two positions in which movement thereof to one position moves the wheels relative to the body of the cleaner to raise the nozzle sufficient to break the seal between the carpet and the nozzle and also locks the converter tool in the converter opening.

Another object is the provision of a conversion arrangement in which the insertion of the converter tool into the converter opening opens the converter passageway valve and unlocks the suction passageway valve for movement to closed position extending across the suction passageway to block off communication between the nozzle and the fan.

Another object is the provision of a manually actuated valve for the suction passageway in which movement of the valve to its closed position extending across the suction passageway adjusts the wheels relative to the body of the cleaner to raise the nozzle for off-the-floor cleaning and also locks the converter tool in the converter opening.

Another object is the provision of adjustable wheels for raising the nozzle for off-the-floor cleaning in which the adjustment of the wheels to nozzle raising position holds the suction passageway valve in closed position extending across the suction passageway.

Another object is the provision of a converter arrangement in which the wheels are adjustable relative to the cleaner body to raise the nozzle for off-the-floor cleaning and the adjustment of the wheels to their nozzle raising position locks the converter tool in the converter opening.

Another object is the provision of the adjustable wheels to raise the nozzle for off-the-floor cleaning in which the wheel mounting mechanism holds the suction passageway valve both in its open and its closed positions.

Another object is the provision of a suction passageway valve arrangement in which opening of

2

the suction passageway valve lowers the nozzle to its on-the-floor cleaning position and releases the converter tool for removal from the converter opening.

Another object is a conversion arrangement in which the removal of the converter tool from the converter opening locks the suction passageway valve in its open position and also locks the adjustable wheels in their on-the-floor cleaning position.

Another object is the provision of a conversion arrangement in which insertion of the converter tool into the converter opening unlocks the wheel adjusting mechanism for movement to the off-the-floor cleaning position.

Another object is the provision of a conversion arrangement in which insertion of the converter tool into the converter opening opens the motor circuit and the nozzle adjusting mechanism recloses the circuit when moved to the off-the-floor cleaning position.

Another object is the provision of a conversion arrangement in which insertion of the converter tool into the converter opening opens the motor circuit and the movement of the suction passageway valve to its closed position recloses the motor circuit.

Another object is the provision of a movable converter receiving tube which operates to control a conversion function in which insertion of the converter tool into the tube opens the motor circuit and movement of the tube to its operative position recloses the motor circuit.

Other objects and advantages of this invention will become apparent as the description proceeds when taken in connection with the accompanying drawings in which:

Figure 1 is a side view of the suction cleaner according to this invention with certain parts broken away to show the details of construction;

Figure 2 is a fragmentary view of the cleaner of Fig. 1 showing the converter tube being inserted to release the converter tube for subsequent movement;

Figure 3 shows the cleaner of Fig. 1 with the converter tool moved to a position to close the suction passageway and raise the rear wheels so as to raise the nozzle for off-the-floor cleaning;

Figure 4 is a detailed cross-sectional view through the converter tube and tool showing how insertion of the converter tool into the converter tube opens the motor circuit;

Figure 5 is a cross-sectional view on line 5—5 of Fig. 6 looking in the direction of the arrows

3

showing how the converter tube is pivoted to the cleaner in the modification of Figs. 6 and 7 as well as the modification of Figs. 1 to 4, inclusive;

Figure 6 is a view similar to Fig. 1 of a modified form of the invention showing how the invention is applied for lowering the front wheels to raise the nozzle for off-the-floor cleaning in a pivoted motor-fan type cleaner; and

Figure 7 shows the cleaner of Fig. 6 with the converter tube in its nozzle raising position.

Referring to Figs. 1 to 4, inclusive, the suction cleaner of this invention comprises a main frame or body 10 mounted for ambulatory movement on front wheels 11 and adjustable rear wheels 12. The frame 10 is provided with a downwardly facing nozzle 13, connected by a suction passageway 14 to the eye 15 of the fan 16 driven by a motor housed within the motor-fan housing 17. Rotatably mounted within the nozzle 13 is an agitator 18 of any well known construction driven by a belt 19 drivingly connected in any suitable manner to a pulley on the shaft of the motor-fan unit. The fan is provided with an exhaust passageway 20 leading to a filter bag 21 having its upper end suitably supported from a propelling handle 22 pivoted to the top of the exhaust passageway 20 at 23.

During normal on-the-floor cleaning the nozzle 13 is supported a suitable distance above the surface covering being cleaned whereby the covering is drawn upwardly against the nozzle 13 by the suction of the fan 16 so as to be contacted by the agitator 18. The combined beating and brushing action of the agitator and the suction of the fan will dislodge dirt and dust from the carpet and the suction of the fan will carry the dust laden air through the suction passageway 14 and fan eye 15 into the fan chamber whereby the fan will discharge it through the exhaust passageway 20 into the filter bag 21 and the dirt will be removed from the air as it passes through the walls of the filter.

For off-the-floor cleaning wherein any suitable dusting tool is connected to the fan eye by means of a flexible hose it is desirable to raise the nozzle above the floor sufficiently to break the seal between the nozzle and the carpet in order that the carpet will not be injured.

For that purpose a converter tube 24 is journaled to the suction passageway 14 about the fan eye 15. Referring to Figs. 1 and 5 the lower end of the converter tube 24 has a lower arcuate end 25 adapted to swivel in the upper arcuate end 26 of the suction passageway 14. The lower end of the converter tube 24 is also provided with an annular flange 27 concentric with the fan eye which swivels in an opening in the inner wall of the suction passageway 14 adjacent the fan eye 15 and concentric thereto. The converter tube 24 is also provided with a cylindrical projection 29 which swivels in an opening 30 in the outer wall of the suction passageway 14. An extension 31 of the converter tube 24 forms a portion of the upper wall of the suction passageway 14 and also a converter passageway valve as will be explained hereinafter. A converter port valve 32 is pivoted to one side wall of the converter tube 24 and is normally biased to closed position by a spring 33.

The converter tube 24 is preferably normally held against pivotal movement by a latch 34 pivoted to the bottom wall of the tube 24 and is spring-biased clockwise by spring 35 so that its hooked lower end 36 engages beneath the stop 37 extending outwardly from the motor-fan

4

casing 17. The end 38 of latch 34 extends through an opening in the lower wall of the tube 24 and is adapted to be engaged by a cam 39 on the inner end of a converter tool 40 which is attached by means of a flexible hose to any suitable cleaning tool.

A second latch 41 is also pivoted to the lower wall of the tube 24 on the same pivot pin as the latch 34 and is spring-biased in a counter-clockwise direction by spring 35 so that its end 41' normally rests against the upper side of stop 37. An offset end 42 of latch 41 extends into a second opening in the lower wall of the tube 24 and is adapted to be projected through that opening by spring 35 to engage behind a shoulder 43 on the lower side of the converter tool 40 when the converter tube 24 is pivoted upwardly so as to remove the end 41' of the latch 41 away from the stop 37 for a purpose which will later appear.

One end of a link 44 is pivoted on a pin 45 on the cylindrical projection 29 eccentric to the pivotal axis of the converter tube 24 at a point above and forwardly of that axis. The other end of link 44 is pivoted to an arm 46 of a rear wheel carriage 47 pivoted at 48 to the under side of exhaust passageway 20. The wheel carriage 47 is biased clockwise by a compression spring 49 as shown. The arrangement is such that when the converter tube 24 is in its normal latched position the link 44 will hold the carriage 47 in the proper position to locate the nozzle 13 at the proper height for optimum cleaning effectiveness. It is to be noted that the bias of spring 49 normally holds the tube 24 in its lowest position. For that reason the latch 34 is not a necessity but has been provided to prevent a non-authorized movement of the tube 24 to its operative or conversion position.

In order to prevent the cleaner from being operated for off-the-floor cleaning until the nozzle 13 is raised and the suction passageway valve 31 is closed a switch 70 (Fig. 4) is provided. The switch 70 may be mounted on the inner wall of the motor-fan casing 17 as shown in Fig. 4. The switch 70 is of a well known type having a button 71 spring-pressed outwardly to close the circuit when in outer position and to open the circuit when pressed inwardly.

The button 71 extends through an opening 72 in the motor-fan casing 17 and through an opening 73 in the inner wall of the converter receiving tube 24 into a position to be contacted by the converter tool 40 as it is inserted into the tube 24. The switch 70 and the opening 73 are so positioned that as the link 44 moves past its over-center position, as will be explained hereinafter, the inner wall of the tube 24 will move free of the pin 71 and permit it to move outwardly to close the motor circuit. The opening 73 is tapered outwardly and the outer end of pin 71 is rounded, as shown in Fig. 4, and the bottom wall of the tube 24 has a cam notch 74 for a purpose which will presently appear.

The wiring diagram has not been shown since any one skilled in the art can connect the switch 70 in the proper circuit with the usual handle mounted manual switch and the motor to close the motor circuit when both switches are closed and open the circuit when either switch is open.

The modification of Figs. 5, 6 and 7 is similar to that of Figs. 1 to 3, inclusive, except that the front wheels are adjustable instead of the rear wheels and the cleaner is of the pivoted motor fan casing type. Where the parts are the same

they have been given the same reference numerals. The cleaner of this modification is of the same general character as that shown in the patent to Burkhardt 2,225,621 dated December 24, 1940.

The cleaner of Figs. 5, 6 and 7 comprises a main frame 50 including a downwardly facing nozzle 51 connected to the fan eye 52 by a suction passageway 53 and having a second tunnel on the opposite end of the motor fan unit for receiving the driving belt for the agitator 54 as in the patent to Burkhardt above referred to. The frame is supported for ambulatory movement by adjustable front wheels 55 and rigidly attached rear wheels 56.

The casing 57 which houses the motor fan unit is pivoted between the suction passageway 53 and the opposite belt receiving tunnel in a manner similar to that shown in the patent to Burkhardt above referred to. As shown in Fig. 5 the fan eye has an outwardly extending flange 58 received in a trunnion bearing 59 suitably secured to the frame 50. Suitable sealing gaskets 60 and 61 are provided to prevent the leakage of air through the trunnion bearing. The flange 27 of the converter tube 24 is also received in the trunnion bearing 59.

The front wheels 55 are carried by offset pintles 62 of a crank shaft 63 pivoted to the rear of the nozzle 51 at 64. The shaft 63 is provided with an offset arm 65 which pivotally receives the lower end of a link 66 pivotally connected at its upper end to the pivot pin 45.

The motor casing 57 is provided with an integral exhaust passageway 67 discharging into a detachable filter bag 68 and with a handle socket 69 rigid with the exhaust passageway 67.

Operation

When it is desired to convert the modification of Figs. 1 to 4, inclusive to off-the-floor cleaning the converter tool 40 is inserted into the converter tube 24. Its lower end will engage the converter port valve 32 and move it to open position as shown in Fig. 2. Simultaneously, the cam 39 will engage the end 38 of the latch 34 and pivot it counterclockwise against the bias of spring 35 and remove its hooked end 36 from below the stop 37 so as to free the converter tube 24 for upward pivotal movement. At the same time the inner end of the converter tool 40 will engage the pin 71 of switch 70 and press it inwardly so as to open the motor circuit.

The converter tube 24 is then pivoted upwardly. The slanted surface on the inner wall of the tube 24 about the opening 73 will engage the rounded end of the pin 71 and press the pin further inwardly and the motor circuit will remain open. At the same time the end 41' of the latch 41 moves away from the upper side of the stop 37 and since the latch 41 is biased counterclockwise by spring 35 the inner end of the hooked end 42 will be brought behind the shoulder 43 of the converter tool 40 and thus lock the converter tool in the tube 24.

If desired, while the tube 24 is being moved upwardly pressure can be applied to the rear of the cleaner to compress the spring 49 so as to aid in the movement of the tube 24 to operative position. Alternatively, the entire moving force can be applied by pressing downwardly on the rear of the cleaner.

As the tube 24 is pivoted upwardly by any one of the foregoing methods the pivot pin 45 moves in the arc of a circle so as to move the link 44 downwardly and pivot the wheel carriage coun-

terclockwise against the bias of the spring 49 until the pin 45 passes its dead center position relative to the pivotal axis of the tube 24 and the lower pivot of link 44. When that occurs the pin 71 of switch 70 will ride free of the inner wall of the tube 24 to permit the pin to move outwardly and close the motor circuit and the spring 49 will pivot the carriage 47 clockwise and positively move the tube 24 to its uppermost position of Fig. 3 where the extension or valve 31 will extend across the suction passageway 14 and close off the suction nozzle 13 from communication with the fan eye 15.

In the position of Fig. 3 the nozzle 13 will have been raised upwardly to a position where no seal will be made between the nozzle and any carpet or other surface upon which the cleaner may be resting.

It is to be noted that in the position of Fig. 3 the spring 49 acts to hold the nozzle in its raised position, holds the converter tube 24 in its uppermost position, and the action of the latch 41 locks the converter tool 40 in place and since the valve 32 is then open and the valve 31 closed it also acts to hold those valves in those positions.

Conversely, the movement of the converter tube 24 to its upper position, and the overcenter mechanism above described, holds the wheels in their adjusted position with the nozzle raised, holds the converter in place, the converter port valve open and the suction passageway valve closed. Additionally, the insertion of the converter tool 40 unlocks the converter tube 24 for movement and thus unlocks the nozzle adjusting mechanism and also the suction passageway valve 31 for movement. Furthermore, movement of the suction passageway valve 31 to its closed position may be said to hold the converter in place and to hold the wheels in their nozzle raising position. Movement of the suction passageway valve 31 to its open position may be said to release the converter and to return the wheel adjusting mechanism to its normal on-the-floor cleaning position. Removal of the converter tool 40 may be said to hold the converter passage valve 31 in its open position and the wheels in their normal on-the-floor cleaning position.

When it is desired to reconvert to on-the-floor cleaning the converter tube 24 may be manually moved clockwise or pressure may be applied to the rear of the cleaner to compress the spring 49 until the link 44 again returns to its dead center position at which time the cam 74 on the inner wall of the tube 24 will engage the pin 71 and open the motor circuit. When the link 44 moves slightly past its dead center position the spring 49 will then positively move the tube 24 to the position shown in Fig. 2 whereby the end 41' of the latch 41 will engage the stop 37 and move the hooked end 42 from behind the shoulder 43 of tool 40 to release the tool 40 for removal from the tube 24. The removal of the tube 40 will permit the latch 24 to take the position of Fig. 1 and the pin 71 to move outwardly and reclose the motor circuit. The nozzle will have been lowered and the cleaner will again be conditioned for normal on-the-floor cleaning.

The modification of Figs. 6 and 7 operates in a similar manner except that as converter tube 24 is moved upwardly, the link 66 moves downwardly to pivot the shaft 63 clockwise and moves the wheels 55 downwardly and the nozzle 51 upwardly until the pin 45 is moved past its dead

center position. At that time the weight of the cleaner will move the tube 24 to its uppermost position of Fig. 7. In this modification the movement of the converter tube 24 may be aided by tilting the cleaner backwardly on the rear wheels 56 whereby the front wheels 55 will drop downwardly by gravity and aid in the movement of the tube 24 upwardly until the link 66 moves past its dead center position. If desired, a light spring may be provided for normally holding the wheels 55 in their upper position and to prevent excess play in the mechanism.

The switch mechanism for controlling the motor circuit has not been shown in this modification but it is to be understood that it is to be provided in a manner similar to that shown in the modification of Figs. 1 to 3, inclusive.

In the modification of Figs. 6 and 7 the weight of the cleaner may be said to hold the wheels in their adjusted position with the nozzle raised, hold the converter tube in its uppermost position, hold the suction passageway valve closed and the converter tool 40 in the tube 24.

While I have shown but two modifications of my invention it is to be understood that these modifications are to be taken as illustrative only and not in a limiting sense. I do not wish to be limited to the particular structure shown and described but to include all equivalent variations thereof except as limited by the scope of the claims.

I claim:

1. A suction cleaner including a body, a downwardly facing nozzle at the forward end of said body, a motor, a fan driven by said motor, said fan including a casing having a fan eye formed in said body, said body having a suction passageway extending between said fan eye and said nozzle, a converter receiving tube swivelled to said body on the axis of said fan eye for communication therewith, latch means carried by said tube and extending into the interior thereof for holding it against swivelling movement, said converter receiving tube being movable from its latched position to an operative position to perform a function in converting the cleaner to off-the-floor cleaning, a converter tool insertable into said converter receiving tube and means on said converter tool operable upon insertion of said tool into said tube for engaging and releasing said latch means.

2. A suction cleaner according to claim 1 including switch means for controlling said motor, said switch means being positioned to be engaged by said converter tool as it is inserted into said tube to open the circuit of said motor and to reclose the circuit upon movement of said tube to its operative position.

3. A suction cleaner including a body, a downwardly facing nozzle at the front end of said body, means for supporting said body for ambulatory movement with said nozzle positioned for on-the-floor cleaning, said supporting means being movably attached to said body for raising said nozzle for off-the-floor cleaning, a motor, a fan driven by said motor, said fan including a casing having a fan eye and being carried by said body, said body having a suction passageway extending between said fan eye and said nozzle, a converter receiving tube mounted on said body for communication with said fan eye, said converter receiving tube being movable from an inoperative position to an operative position, motion transmitting means extending between said converter receiving tube and said supporting

means and operable upon movement of said converter receiving tube to its operative position for moving said supporting means relative to said body to raise said nozzle, a converter tool insertable into said tube, latch means carried by said tube and means operable in response to movement of said converter receiving tube to its operative position for actuating said latch means to latch said tool in said tube.

4. A suction cleaner including a body, a downwardly facing nozzle at the front end of said body, a motor, a fan driven by said motor, said fan including a fan eye carried by said body, said body having a suction passageway extending between said nozzle and fan eye, a converter receiving tube carried by said body for communication with said fan eye, a valve in said tube and normally closing off communication between said tube and fan eye, a second valve movable from an open position to a position extending across said suction passageway to close off communication between said nozzle and fan eye, latch means for locking said second valve in open position, a converter tool insertable into said tube, and means on said tool for opening said first valve and for unlocking said second valve as it is inserted into said tube.

5. A suction cleaner including a body, a downwardly facing nozzle at the front end of said body, means for supporting said body for ambulatory movement, said supporting means being movably attached to said body for raising said nozzle, a fan including a fan eye carried by said body, said body having a suction passageway extending between said fan eye and nozzle, means defining a converter receiving opening for communication with said fan eye, a converter tool receivable in said opening, a valve associated with said suction passageway having an open position and a closed position extending across said suction passageway for closing off communication between said nozzle and fan eye, latch means adjacent said opening, means operable upon movement of said valve to its closed position for actuating said latch means to latch said tool in said opening and motion transmitting means connecting said valve and supporting means and operable upon movement of said valve from its open to its closed position for moving said supporting means relative to said body to raise said nozzle.

6. A suction cleaner according to claim 5 in which said motion transmitting means is also constructed to hold said valve in its closed position when said supporting means is in its nozzle raising position.

7. A suction cleaner including a body, a nozzle carried by said body, means for supporting said body for ambulatory movement, said supporting means being movably secured to said body to selectively position said nozzle in a position for on-the-floor cleaning or in a higher position for off-the-floor cleaning, a fan carried by said body, said body having a suction passageway extending between said nozzle and the suction side of said fan, means defining a converter receiving opening for communication with the suction side of said fan, a converter tool receivable in said opening, a valve associated with said suction passageway having an open position and closed position in which said valve extends across said suction passageway to close off communication between said nozzle and the suction side of said fan, latch means adjacent said opening for locking said tool in said opening and means operable by move-

ment of said valve to its open position for releasing said latch means and a linkage mechanism connecting said valve and said supporting means and operable by movement of said valve to its open position to move said supporting means to its on-the-floor cleaning position.

8. A suction cleaner including a body, a nozzle on said body, front and rear wheels attached to said body, said rear wheel attaching means including a carriage pivoted to said body and spring biased to urge said wheels away from said body, a fan on said body, said body being formed with a suction passageway connecting said nozzle to the suction side of said fan, a valve associated with said suction passageway movable from an open position to a closed position extending across said suction passageway to shut off communication between said nozzle and fan, and a linkage mechanism connecting said valve with said carriage, the arrangement being such that said linkage lies on one side of an overcenter position when said valve is open and on the other side when said valve is closed whereby the spring bias of said carriage resists movement of said valve from either its closed position or its open position and movement of said valve to its open position permits the spring bias of said carriage to lower said wheels and movement of said valve to its closed position holds said wheels in a higher position so as to raise said nozzle for off-the-floor cleaning.

9. A suction cleaner including a body, a nozzle on said body, wheels for supporting said body for ambulatory movement, said wheels being movably attached to said body for selective movement relative thereto to position said nozzle at a lower position for on-the-floor cleaning and at a higher position for off-the-floor cleaning, a motor and fan driven thereby on said body, said body being formed with a suction passageway connecting said nozzle with the suction side of said fan and with a converter tube for communication with the suction side of said fan, a converter tool insertable into said tube, said tube being manually actuatable, a linkage mechanism connected to said wheels and tube for moving said wheels to either the nozzle raising or nozzle lowering positions and switch means for controlling said motor located in a position to be actuated to open position by insertion of said converter tool into said tube and to be actuated to closed position by movement of said tube to its nozzle raising position.

10. A suction cleaner including a body, a nozzle on said body, wheels carried by said body for supporting it for ambulatory movement in on-the-floor cleaning, a motor and fan driven thereby on said body, said body being formed with a suction passageway connecting said nozzle to the suction side of said fan and with a converter tube for communication with the suction side of said fan, a converter tool insertable into said tube, a valve associated with said suction passageway and movable from an open position to a closed position extending across said suction passageway to close off communication between said nozzle and fan, said tube being manually actuatable for moving said valve to either of its positions and switch means for controlling said motor positioned to be actuated to open position by the insertion of said converter tool into said tube and to be actuated to closed position by movement of said tube to its valve closing position.

11. A suction cleaner including a body, a nozzle on said body, wheels carried by said body for supporting it for ambulatory movement in on-the-floor cleaning, a motor and fan driven thereby on said body, said body being formed with a suction passageway connecting said nozzle to the suction side of said fan, a converter receiving tube movably secured to said body for movement from an inoperative position to an operative position for performing some function in converting the cleaner to off-the-floor cleaning and switch means for controlling said motor positioned to be actuated to open position upon insertion of said tool into said tube and to be actuated to closed position upon movement of said tube to its operative position.
12. A suction cleaner comprising, a body, a downwardly facing nozzle at the front of said body, front and rear wheels attached to said body for supporting it for ambulatory movement, a horizontal axis motor driven fan including a fan eye on said body, said body being formed with an upwardly and rearwardly extending suction passageway between said nozzle and said fan eye, a converter receiving tube pivoted to the upper end of said suction passageway on the axis of said fan and communicating with said fan eye, an extension on said tube normally forming a portion of the upper wall of said suction passageway and movable downwardly across said suction passageway when said tube is pivoted upwardly to close off communication between said nozzle and fan eye, said rear wheels being carried by a carriage pivoted to said body, spring means for biasing said wheels away from said body, an arm rigid with said carriage and extending forwardly from the pivot thereof, a link having its lower end pivoted to the forward end of said arm and its upper end pivoted to said tube above and forwardly of its pivotal axis when said tube is in its normal position whereby upward pivotal movement of said tube will move said carriage counterclockwise against the bias of said spring means until the upper pivot point of said leg passes a line extending between the pivotal axis of said tube and the lower pivot point of said leg and thereafter said spring means will positively move said tube to its uppermost position with said extension extending across said suction passageway and said nozzle raised upwardly and said tube is held in each of its positions by the bias of said spring means.
